UNITED STATES PATENT OFFICE.

JOHN J. COIT, OF VENICE, CALIFORNIA.

TROLLEY-POLE CONTROLLER.

No. 879,934.

Specification of Letters Patent.

Patented Feb. 11, 1908.

Application filed October 20, 1906. Serial No. 339,781.

To all whom it may concern:

Be it known that I, JOHN J. COIT, a citizen of the United States, residing at Venice, in the county of Los Angeles and State of California, have invented new and useful Improvements in Trolley-Pole Controllers, of which the following is a specification.

This invention relates to that class of controllers which are pneumatically operated; and the object thereof is to provide a durable, simple and efficient device for raising and lowering the trolley pole of an under-running trolley by pneumatic pressure. I accomplish this object by means of the device described herein and illustrated in the accompanying drawings in which:

Figure 1— is a longitudinal section of an under-running trolley showing the trolley wheel in place on the wire. Fig. 1^a— is a diagrammatic plan of the trolley pole and controlling mechanism broken away in places for clearness of illustration. Fig. 2— is an enlarged cross sectional detail on line 2—2 of Fig. 1. Fig. 2^a— is a section on the line 2^a—2^a of Fig. 2 with the piston and stem omitted. Fig. 3— is an enlarged cross sectional detail on line 3—3 of Fig. 1. Fig. 4— is a longitudinal sectional detail through the control valve secured to the outer end of the trolley pole, with the valve in its operative position for lowering the pole. Fig. 5— is a longitudinal detail of the differential valve connected to the trolley base in its operative position for lowering the pole. Fig. 6— is a longitudinal section of an under-running trolley illustrating a modified form of operation. Fig. 7— is a longitudinal sectional detail of the control valve illustrated in Fig. 6 in its operative position for lowering the wheel from the wire. Fig. 8— is a longitudinal sectional detail of the differential valve illustrated in Fig. 6 in its operative position for lowering the wheel from the wire. Fig. 9— is a longitudinal section illustrating another modification.

Referring to the drawings 10 represents a hollow base block, preferably cylindrical in form, which is secured to the top of the car (not shown) having a central orifice 11, through which projects a swivel block 12 to which is detachably secured the trolley base 13 by means of bolts 14, so that the base can be removed from the swivel block without disturbing the same. Balls 15 provide a bear-

ing between the base block 10 and the swivel block. The swivel block is held in position in the base by set screws 16 which project through the base block and into the groove 17 formed in the outer surface of the swivel block. In the center of the swivel block is a channel 18, the lower part of which is enlarged for the reception of the upper end of pipe 19 which leads to a source of compressed air supply (not shown). A gland 20 provides an air tight packing between the swivel block and pipe 19.

At opposite ends of the trolley base are the air cylinders 21 and 22 and in these cylinders are pistons 23 and 24 which are connected by a stem 25, in the central portion of which is formed a rack 26 which is engaged by a toothed sector 27 secured to the base 28 of the trolley pole 29, whereby when the rack is moved to the left the free end of the trolley pole will be moved upwardly, and when it is moved to the right the free end of the trolley pole will be moved downwardly.

Secured to the base 13 is the differential valve chamber 30, one end of which is much larger than the other end as best shown in Figs. 1 and 5. In the larger end of this chamber is a piston 31 and in the smaller end is a piston 32. These pistons are connected by a stem 33 which projects through piston 32 and after passing therethrough is reduced in size to form a collar or abutment 34 near the piston. On the outer end of this stem is a collar 35 and between collars 34 and 35 is a slide valve 36, which when in the position shown in Fig. 1 connects exhaust port 37 with an L-shaped channel 38, which channel is cored in the casing and is shown in dotted lines in Fig. 1 and opens into the outer end of chamber 22, whereby the same is connected to the outer air or to exhaust.

Adjacent to exhaust port 37 at an equal distance therefrom with channel 38 is a channel 39 which is connected by a pipe 40 (shown in dotted lines in Fig. 1 and in full lines in Fig. 1^a) with a channel 41 which opens into the outer end of chamber 21, so that when the slide valve is in the position shown in Fig. 1 the outer end of chamber 21 is connected to pressure.

In base 13 is a channel 42, one end of which registers with channel 18 in the swivel block and one end opens into the smaller end of the differential valve chamber between the

end thereof and piston 32, whereby pressure is conveyed into the smaller end of the differential valve chamber and through the connections therewith to the outer end of chamber 21. Connected with channel 42 is a channel 43 shown in dotted lines in Fig. 3 and which connects with channel 42 at 44 in Fig. 1. Channel 43 is connected by pipe 45 with channel 46 in trunnion 47 of the trolley pole base (see Fig. 2). The inner end of channel 46 is connected by a pipe 48 with control valve chamber 49, the casing 50 of which is secured upon the upper end of the trolley pole.

15 The casing of the control valve chamber is provided with a bushing 51 in which is port 52 which registers with a port 53 in the casing, which last port is in communication with the open air. Said bushing also has a port 54 therein which opens into channel 55 (see Figs. 1 and 2^a) which is connected by pipe 56 with the inner end of channel 57 in trunnion 58 of the trolley pole base shown in dotted lines in Fig. 2, the construction being the same as channel 46 and trunnion 47. The outer end of this last channel is connected by pipe 59 with port 60 which opens into the outer end of the larger end of the differential valve chamber, whereby when the pistons in the differential valve chamber and the pistons in the control valve chamber are in the position shown in Fig. 1, the same pressure is in both ends of the differential valve chamber.

35 In the control valve chamber is a piston 61 which has a stem 62 extending therethrough. The outer end of this stem may reciprocate through an opening in the outer end 63 of the control valve chamber. The inner end of the stem is provided with collars 64 and 65 between which is carried a slide valve 66. To the outer end of the casing of the control valve chamber is pivotally secured the trolley harp 67 in which is secured in the usual manner the trolley wheel 68 which runs upon the feed wire 69. The trolley harp has an arm 70, which when the trolley wheel is held in contact with the feed wire, bears against the outer end of stem 62 of the piston of the control valve and prevents the piston from moving toward the outer end of the chamber, thereby keeping port 54 open to pressure.

55 In the operation of a car equipped with my controller, it may be remarked that when the car is in the barn the control slide valve will be in the position shown in Fig. 4 and the differential slide valve will be in the position shown in Fig. 5, in which positions chamber 21 is thrown to exhaust and chamber 22 to pressure, thereby lowering the trolley pole from the feed wire. When the air pressure is turned into pipe 19, a cock thereon (not shown) being opened for that purpose, the

air pressure would keep the pistons in the control valve chamber and in the differential valve chamber in the positions shown in Figs. 4 and 5, and the trolley harp would be held in the position shown in Fig. 4. The conductor desiring to operate the car would then seize trolley rope 71, which is connected to an arm 72 secured to the harp, and would pull upon the same and bring the harp to the position shown in Fig. 1, thereby moving the slide valve in the control valve chamber to uncover port 54, whereby pressure would be again admitted into the larger end of the differential valve chamber through port 60, and the pressure upon piston 31, which is much larger in area than piston 32, would cause the movement of these pistons to the position shown in Fig. 1 whereby chamber 22 would be thrown to exhaust and chamber 21 to pressure, whereupon he would guide the trolley wheel to the feed wire in the usual manner. To enable the difference of area between pistons 31 and 32 to be effective I provide a port 73 in the casing of the differential valve chamber to connect the space between the two pistons at all times to the open air. As long as the trolley wheel is upon the feed wire it will be seen that the pneumatic pressure will hold the harp in the position shown in Fig. 1, but should the trolley wheel accidentally become disengaged from the feed wire the air pressure upon the piston in the control valve chamber will instantly throw the harp, piston and slide valve to the position shown in Fig. 4, thereby throwing the larger end of the differential valve chamber to exhaust, which permits the pressure on piston 32 to instantly move the pistons in the differential valve chamber to the position shown in Fig. 5, thereby throwing chamber 21 to exhaust and chamber 22 to pressure. To prevent any jar upon the trolley pole when chamber 22 is thrown to pressure and chamber 21 to exhaust I provide a spiral spring 74 coiled around stem 25 in chamber 22 between piston 24 and the end of the chamber. The connection between pipes 45 and 59 with the trunnions of the trolley pole base are provided with packing glands 75 and 76. The inner or contiguous ends of the casing forming chambers 21 and 22 are united by side walls 77 and 78 which in the center thereof project upwardly and form bearings for the trunnions of the trolley pole base which are mounted therein and sector 27 projects downwardly between said walls. Below stem 25 is a small lubricating box 79 in which waste 80 may be kept, which waste is saturated with oil so that the stem 25 may be lubricated.

In Figs. 6, 7 and 8 I have shown my device slightly modified, the only changes however being that port 54 and channel 55 are now

placed at the rear of the control valve chamber and are marked with numerals, the port 81 and the channel 82, and chamber 22 is now connected to the port corresponding to port 39 which is marked 83 and chamber 21 is connected to the port corresponding to port 38 which is marked 84. In this construction it will be seen that when the trolley wheel is on the feed wire the 10 larger end of the differential valve chamber will be thrown to exhaust and when the trolley wheel accidentally leaves the feed wire the movement of the slide valve in the control valve chamber will throw the larger 15 end of the differential valve chamber to pressure which will cause the movement of the slide valve in that chamber so as to throw chamber 21 to exhaust and chamber 22 to pressure. The operation of this construction 20 is much slower than the preferred form and for that reason is not as good as the preferred form of construction.

In Fig. 9 I have shown a still further modification in which the action of raising and lowering the free end of the trolley pole is performed by the use of one air cylinder. In this modification the construction is in all respects similar to that shown in Fig. 1, except that air cylinder 22 of Fig. 1 is dispensed with and the outer end passes through a guide 85 and a spring 86 surrounds the stem beyond the guide. A nut 83 is substituted on the outer end of stem 25 for piston 24 so as to regulate the tension of spring 86 so that, should the air give out the trolley could be operated by the spring 86. A further change in the construction is that chamber 21 is provided with ports 87 and 88 being at each end thereof and the casing of 40 the smaller end of the differential valve chamber is provided with ports 89 and 90. Port 89 is connected to port 88 by pipe 91 and port 87 is connected to port 90 by pipe 92. A stuffing box 93 is provided to make a 45 tight fit around stem 25 where it passes through the casing of chamber 21. In this construction the operation is the same as that of Fig. 1, the ends of chamber 21 being thrown alternately to exhaust or pressure 50 in the same manner as chambers 21 and 22 were before thrown to exhaust or pressure.

Having described my invention what I claim is:

1. In a pneumatic trolley controller, a 55 trolley pole; pneumatically operated means secured thereto to elevate the free end thereof; pneumatically operated means secured to the trolley pole to depress the free end thereof; a valve controlled connection between said pneumatically operated means to connect one of said means to pressure and the other to exhaust; and controlling means operable by the trolley to hold the elevating

means to pressure and the depressing means to exhaust when the wheel is on the feed 65 wire, and to permit the reversal of pressure and exhaust when the wheel accidentally leaves the feed wire.

2. A trolley controller, consisting of oppositely disposed cylinders; pistons in said 70 cylinders; a trolley pole; a connection between said trolley pole and said pistons; pneumatically operated mechanism for alternately admitting compressed air to the outer end of one cylinder and for throwing the 75 outer end of the other cylinder to exhaust; and pneumatically operated mechanism controlled by the harp for controlling the mechanism which controls the direction of the air to said cylinders.

3. A trolley pole controller, comprising a 80 trolley base; oppositely disposed cylinders secured to said base; pistons in said cylinders; a stem extending from one piston to the other, said stem having a rack in the face thereof; a trolley pole pivotally connected to the trolley base and having a depending toothed sector engaging the rack on said stem; pneumatically operated mechanism for alternately admitting compressed air to 85 the outer end of one cylinder and for throwing the outer end of the other cylinder to exhaust; and pneumatically operated mechanism controlled by the harp for controlling the mechanism which controls the direction 90 of the air to said cylinders.

4. In a pneumatic trolley controller, a 100 trolley pole having the harp thereof pivotally connected thereto; pneumatically operated means secured thereto to elevate the free end thereof; pneumatically operated means secured to the trolley pole to depress the free end thereof; a connection between said elevating and depressing mechanism; a slide 105 valve mechanism on said trolley pole, said slide valve controlling said connection and said slide valve having a stem projecting through the valve chamber casing toward the harp; and an arm secured to said harp engaging said stem to hold the valve to connect the elevating mechanism to pressure and the depressing mechanism to exhaust when the wheel is on the feed wire and to permit the reversal of pressure and exhaust when the wheel leaves the feed wire.

5. A trolley pole controller, comprising a 110 trolley base; oppositely disposed cylinders secured to said base; pistons in said cylinders; a stem extending from one piston to the other, said stem having a rack in the face 115 thereof; a spring surrounding said stem in one of said chambers; a trolley pole pivotally connected to the trolley base and having a depending toothed sector engaging the rack on said stem; pneumatically operated mechanism for alternately admitting com- 120 125

pressed air to the outer end of one cylinder and for throwing the outer end of the other cylinder to exhaust; and mechanism pneumatically operated and controlled by the
5 harp for controlling the mechanism which controls the direction of the air to said cylinders.

In witness that I claim the foregoing I have hereunto subscribed my name this 12th day of October, 1906.

JOHN J. COIT.
